UNITED STATES PATENT OFFICE

133,920

DESIGN FOR A SIDING

Clayton Beeson, Joliet, Ill., assignor to The Ruberoid Co., New York, N. Y., a corporation of New Jersey

Application April 11, 1941, Serial No. 100,323

Term of patent 14 years

To all whom it may concern:

Be it known that I, Clayton Beeson, a citizen of the United States and resident of Joliet, in the county of Will and State of Illinois, have invented a new, original, and ornamental Design for a Siding, of which the following is the specification, reference being had to the accompanying drawing, forming a part thereof, in which:

Figure 1 is a face view of a siding unit;

Figure 2 is a section thereof on the line 2--2 of Figure 1; and

Figure 3 is a fragmentary face view of a siding, showing my new design.

The essential feature of my design resides in the specific grouping of the large and small irregular blocks in association with the simulated faces of wire cut half bricks in the lower corners of the unit shown in Fig. 1.

I claim:

The ornamental design for a siding, substantially as shown and described.

CLAYTON BEESON.
